UNITED STATES PATENT OFFICE.

ALBERT FRANK HOLLIDAY, OF WIGAN, ENGLAND.

VARIABLE ELECTRIC CONDENSER, VARIOMETER, AND THE LIKE.

Application filed December 8, 1924, Serial No. 754,579, and in Great Britain December 15, 1923.

This invention relates to variable electric condensers, variometers and the like apparatus in which one member has a limited rotation relatively to another.

- 5 The object of this invention is to provide a condenser or the like wherein the effect of the capacity of the operator's hands when adjusting the operating spindle is reduced to zero.
- 10 According to the present invention in a variable condenser, variometer or the like having the shaft of its movable elements insulated from the operating spindle all metallic elements lying between the insulating member and the operating spindle are provided with an earth connection.

In condensers wherein the movement of the operating spindle is equal to the movement of the movable element the metallic parts lying between the insulating member and the spindle are normally interconnected but in those condensers which employ gearing between the spindle and the movable element to multiply the movement of the one relatively to the other, it is necessary to provide means to ensure that at all times there is metallic connection between the gear members.

The invention is more particularly described with reference to the accompanying drawings, in which:—

Figure 1 shows a plan view of the instrument.

Figure 2 shows a further plan view with the scale and mounting panel removed.

Figure 3 is an elevation of the device.

The condenser comprises in the usual manner a pair of insulating plates 1, 2, spaced apart by suitable members such as screws 3, 4 and 5 which carry a set of fixed vanes 6. The stud 5 further carries a terminal 7 to which a conductor may be connected.

The rotary vanes 8 are mounted on a sleeve 9 provided with a threaded spindle 10 and mounted at one end in a bearing 11 carried by the insulating plate 1.

The operating spindle 12 and handle 13 are displaced from the axis of the spindle 10 and connected with the same by gearing, a pinion 14 on the spindle 12 meshing with a further pinion 15 on the spindle 10, the gear ratio being such that on the rotation of the movable vanes 8 through 180° from the minimum to the maximum position the operating handle 13 and spindle 12 together with the scale 16 rigidly secured thereto

have rotated through one complete revolution. In this manner the graduations of the scale may be increased to double that obtainable when the scale is mounted directly on the spindle of the rotary members.

The pinion 15 may have teeth cut on only a portion of its surface as shown in Fig. 2 or alternatively may be provided with teeth completely round its periphery, the space between the adjacent teeth being filled up as desired to act as stops for the relative movement of the two wheels.

The mounting of the spindle 10 carrying the movable members 8 in the insulating sheet 2 comprises an insulating collar 17 into which the threaded spindle 10 is screwed and a further threaded spindle 18 projecting between the opposite end of the insulating collar 17 and the insulating sheet 2. Mounted on the spindle 18 is the gear 15 below the insulating collar 17, the latter thus completely insulating the gear 15 from the spindle 10 and vanes 8. Mounted between the gear 15 and the insulating plate 20 is a spring washer 20 and a strip of foil, for example of copper 21.

The copper strip 21 extends between the spindle 18 and the spindle 12 carrying the operating handle 13 and is provided with a turned over portion 22 to which, if desired, an earth wire can be connected. In this manner all metallic parts on the operating side of the collar 17 are metallically connected.

A metal plate such as an aluminium disc 23 is mounted on the face of the panel 24 on which the condenser is mounted to avoid the effect of hand capacity, as is well known.

In the construction illustrated in Figs. 1 and 3 the metal disc 23 is adjustably but rigidly mounted on the panel 24 and metallically connected with the spindle 12. The disc 23 is further provided with an indicating mark 25 which is adapted to be used as 100 a zeroing indicator for the graduated scale 16 mounted on the spindle 12.

I declare that what I claim is:

1. In a variable electric tuning instrument, the combination of a stationary coupling element, a coupling element movable relatively to said stationary element, an operating spindle having a handle for said movable element, means insulating said movable element from said operating spindle and connecting means adapted to connect all metallic members lying between said insulating

means and the handle of said spindle to earth.

2. In a variable electric tuning instrument the combination of a stationary coupling element, a coupling element movable relatively to said stationary element, an operating spindle having a handle for said movable element, means insulating said movable element from said operating spindle, gears between said operating spindle and said movable element and means to interconnect metallically at all positions of said gears, all metallic parts lying between said insulating element and the handle of said spindle.

15 3. In a variable electric tuning instrument the combination of a stationary coupling element, a coupling element movable relatively to said stationary element, an operating spindle having a handle for said movable element, means insulating said movable element from said operating spindle gears between said operating spindle and said movable element and means to interconnect metallically at all positions of said gears all 20 metallic parts lying between said insulating element and the handle of said spindle, and means on said interconnection member to attach said member to earth.

30 4. In a variable electric tuning instrument or the like electrical coupling device the combination of an insulating frame, a stationary coupling element mounted on said frame, a rotatable shaft journaled on said frame, a movable coupling element rigidly fixed to said shaft, an insulating member secured to one end of said shaft a gear mounted co-axially with said shaft and insulated therefrom by said insulating member, an operating spindle for said movable element, a gear on said spindle meshing with the gear on said shaft, a conductive strip in metallic contact with said spindle and with said gear on said shaft and means on said strip for an earth connection.

45 5. In a variable electric tuning instrument the combination of an insulating frame, a stationary coupling element mounted on said frame, a rotatable shaft journalled on said frame, a movable coupling element rigidly fixed to said shaft, an insulating member secured to one end of said shaft, a gear mounted co-axially with said shaft and insulated therefrom by said insulating member, an operating spindle for said movable element, a gear on said spindle meshing with the gear on said shaft, a conductive strip in metallic contact with said spindle and with said gear on said shaft means on said strip for an earth connection an operating handle fixed to said operating spindle, and a graduated scale rotatable with said spindle.

6. In a variable electric tuning instrument the combination of an insulating frame, a stationary coupling element mounted on said frame, a rotatable shaft journaled on said frame, a movable coupling element rigidly fixed to said shaft, an insulating member secured to one end of said shaft, a gear mounted co-axially with said shaft and insulated therefrom by said insulating member, an operating spindle for said movable element, a gear on said spindle meshing with the gear on said shaft, a conductive strip in metallic contact with said spindle and with said gear on said shaft, means on said strip for an earth connection, an operating handle fixed to said operating spindle, a graduated scale rotatable with said spindle and a metal plate fixed to said frame and in metallic connection with said operating spindle.

7. In a variable electric tuning instrument the combination of an insulating frame, a stationary coupling element mounted on said frame, a rotatable shaft journalled on said frame, a movable coupling element rigidly fixed to said shaft, an insulating member secured to one end of said shaft, a gear mounted co-axially with said shaft and insulated therefrom by said insulating member, an operating spindle for said movable element, a gear on said spindle meshing with the gear on said shaft, a conductive strip in metallic contact with said spindle and with said gear on said shaft, means on said strip for an earth connection, an operating handle fixed to said operating spindle, a graduated scale rotatable with said spindle and a metal plate fixed to said frame and in metallic connection with said operating spindle and an indicating mark on said frame.

8. In a variable-electric tuning instrument the combination of an insulating frame a stationary coupling element mounted on said frame, a rotatable shaft journalled on said frame, a coupling element fixed to said shaft and movable relatively to said stationary element, an insulating member secured to one end of said shaft, a gear mounted coaxially with said shaft and insulated therefrom by said insulating member, an operating spindle for said movable element, a gear mounted on said operating spindle and meshing with the gear mounted on said shaft, an abutment arranged on the teeth of one of said gears to limit the relative rotation of the movable member, a conductive strip in metallic contact with said spindle and with said gear on said shaft and means on said strip to secure an earth connection thereto. 105 110 115 120

In witness whereof, I have hereunto signed my name this 6th day of November, 1924.

me this 6th day of November, 1924.
ALBERT FRANK HOLLIDAY.
